CORN SHELLER

John A. Erickson, Jackson, Mich.

Application July 10, 1937, Serial No. 152,929

5 Claims.

(Cl. 130—6)

This invention relates to a device for removing dried corn from its cob and more particularly to a device which separates the shelled corn, the chaff and the cobs.

5 It is the purpose of the present invention to provide a corn sheller particularly for farm use which is readily portable yet effective and efficient.

An object of the invention is to provide a corn sheller wherein the corn is removed from the cob and the cob simultaneously moved axially of the sheller to eject it from the machine.

Another object of the invention is to provide a corn sheller having a shelling cylinder wherein 15 mechanism is provided for urging ear corn fed to the cylinder thereagainst.

A further object of the invention is to provide a shelling cylinder having spirally arranged knobs thereon.

20 Still another object of the invention is to provide a shelling cylinder having a plurality of sheared edges projecting therefrom, some of said edges being spirally disposed and others of said edges being axially disposed.

25 These and other objects will be apparent from the following specification when taken from the accompanying drawing in which,

Fig. 1 is a perspective view of the invention in operation;

30 Fig. 2 is a vertical section through the upper portion thereof perpendicular to the shelling cylinder;

Fig. 3 is a perspective view of the shelling cylinder;

35 Fig. 4 is a developed view of the surface of an alternative form of shelling cylinder;

Fig. 5 is a vertical section through the blower and the shaker screen for removing the chaff from the corn just before it drops into a container below the cylinder, and

40 Fig. 6 is an enlarged section on the line VI—VI of Fig. 4.

Referring particularly to the drawing, the reference character 1 indicates a frame on which the sheller is mounted. The machine comprises a housing 2 in which is rotatably mounted a shelling cylinder 3 on a shaft 4, the shelling cylinder 3 having helically mounted thereon a plurality of knobs 5. The knobs 5 may be as illustrated in Figs. 2 and 3 but preferably are as illustrated in Fig. 4, formed by shearing a plurality of edges 6 in a hollow sheet metal cylinder and forcing the sheared edges outwardly to provide knobs 7. The knobs 7 are preferably formed and positioned prior to the forming of a flat

plate into the cylinder 3. The knobs 7 are disposed helically, the pitch thereof being preferably between three and four times the diameter of the cylinder. While the sheared edges 6 for the most part extend helically toward the outlet 5 end of the cylinder, as will be explained later, some of the projections 7 have their sheared edges 6 projecting axially of the cylinder. The cylinder 3 is rotated by a driving pulley 8 mounted outside of the body 2 on one end of the shaft 4. 10

Mounted over the shelling cylinder 3 is a shell- 15 ing sleeve 9 which is elongated and substantially co-extensive along its major axis with the shelling cylinder 3. The shelling sleeve 9 has a curved cross-section in planes parallel to its minor axis and perpendicular to the shaft 4. The major axis of the shelling sleeve 9 is inclined toward the right or outlet end of the shelling cylinder 3 and its minor axis is inclined downwardly and forwardly as disclosed 20 in Fig. 1 in such a manner as to make the forward edge of the sleeve 9 closer to the cylinder 3 than the rear edge. Hooks 10 normally resting against the outside of the body and against an interior, inclined surface 11 support the sleeve 25 9 in the position just described but in such a manner that it may slide upwardly and forwardly along the inclined surface 11 should the inward pressure by ear corn or corn cobs between the cylinder 3 and the sleeve 9 become 30 sufficiently great. The upward and forward movement of the sleeve 9 is yieldably resisted by springs 15, disposed about pins 16 projecting parallel to the surface 11, rigidly connected to the sleeve 9 and slidably disposed in openings 35 in the outer ends of upwardly projecting brackets 17, secured by bolts 18 to the forward side of the body 2. It will be clear that the pins 16 in addition to supporting the springs 15 also guide the sleeve 9 as it moves. Mounted above 40 and to the left on the inlet side of the body 2 is a hopper 19 for receiving ear corn and feeding it to the top of the shelling cylinder 3. As disclosed in Figs. 1 and 2 the hopper 19 is wider at the left or inlet side than it is at the right 45 or outlet side, the narrow side being approximately in alignment with the mid-portion of the shelling cylinder 3. The purpose of the irregular shape is to limit to one at a time the entrance of ears of corn to that portion of the shelling 50 cylinder 3 to the right of the hopper 19 and covered by the shelling sleeve 9 but to insure at the same time a constant movement of ears.

As corn is removed from the cobs by the shelling cylinder 3 it falls down past the shelling cyl- 55

inder 3 and is guided by the inwardly diverging lower side portions of the body 2 to a shaker screen 20 which is suspended by arms 21 from pivots 22 mounted in the sides 23 of the trough 24 which opens to the rear. The screen 20 is vibrated by an eccentric 25 driven by the shaft 26 on which is mounted a blower 27 disposed in a housing 28. As the shaker screen 20 is vibrated shelled corn falls downwardly through an opening 29 in the bottom of the trough 24 into a suitable container such as a basket 30. The chaff does not pass through the shaker screen 20 but is removed by the blast of air delivered by the blower 27, out of the rear end of the trough 24. The rear pivot 22 may be disposed in alternate openings 31 in the sides of the trough 24 to change the inclination of the shaker screen 20 should such a change be desired. It will be observed that in operation the blast of air created by the blower 27 serves to assist in the sifting of the shelled corn from the chaff by passing upwardly through the shaker screen 20 and preventing any of the smaller particles of the chaff from dropping through with the shelled corn.

25 The source of power for driving the shelling roller 3 and blower 27 is an electric motor 35 supported from the frame 1 and having mounted on its driving shaft 36 a driving pulley 37. A driving belt 38 passes around the pulley 31, the pulley 8 on the end of the shaft 4 of the shelling cylinder 3 and the pulley 39 on the end of the shaft 26 of the blower 27. An additional belt tightening pulley 40 is provided.

30 In operation, as ear corn is fed by the hopper 19 it moves onto the top of the left half of the shelling cylinder, that is, the portion directly below the hopper 19. The spiral arrangement of the knobs 7 on the cylinder 3 serves to feed the ears of corn toward the right or outlet end of the cylinder. 35 The left half of the portion of the shelling cylinder 3 to the right of the hopper 19 and beneath the shelling sleeve 9 has approximately 25% of the shearing edges 6 of the spirally arranged knobs 7 arranged parallel to the axis of the cylinder rather than helically. The right half of the last named portion of the shelling cylinder 3 has approximately 50% of the shearing edges 6 of the spirally arranged knobs 7 arranged parallel to the axis of the cylinder 3 rather than helically. The helical arrangement of the shearing edges 6 and the knobs 7 is to feed the ears of corn to the right or outlet side of the shelling cylinder 3 although they do produce some shelling action. As the corn passes the right edge of the hopper 19 and comes 40 adjacent that portion of the cylinder 3 on which approximately 25% of the edges 6 are arranged parallel to the axis of the cylinder 3 the ears are rotated by the axially extending edges and further shelled. As it moves to the last quarter, more or less, of the shelling cylinder 3 on which approximately 50% of the edges 6 are disposed parallel to the axis of the cylinder 3, the ears are further rotated and the shelling is completed. While the ears are between the shelling cylinder 3 and the shelling sleeve 9 they are subjected to pressure which assists in the shelling and axial feeding. To this end the sleeve 9 is so arranged with respect to the cylinder 3 that even bare cobs will be subjected to pressure exerted on the sleeve 9 by the springs 15. The pressure exerted by the springs 15 is made more effective by the wedging action which takes place as ears are somewhat wedged between the converging surfaces of the cylinder 3 and the sleeve 9, both toward the front of the machine and toward the outlet side. The shelled

5 cobs are then ejected from the outlet or right side of the machine as viewed in Fig. 1. In order to catch any chance pieces of corn that may be ejected from the outlet with the cobs, a trough 42 having an inclined bottom is secured to and communicates with the body 2 and has across the upper portion thereof a screen 43. Thus cobs move across the screen 43 while any corn that might be moved out with the cobs falls through the screen 43 into the lower portion of the body 2 10 and onto the shaker screen 20.

15 Another feature of the invention is the tipper 44 mounted at the hub of the pulley 8. The tipper 44 is in the form of a hollow cone supported adjacent its apex and is provided at the interior thereof with knife blades 45. Thus should it be desired to use the corn, which is being shelled, for seed the tips of each ear of corn, at which imperfectly formed grains usually appear, may be inserted in the tipper 44 to remove the imperfectly formed 20 grains before the ears are placed in the hopper 19.

25 The present corn sheller in addition to being light in weight, inexpensive and portable has the advantage that it requires only a small amount of power to operate it so that a fractional horse power motor may be used. While the sheller described is primarily designed for farm or domestic use, it is not intended that the invention be so limited but that the principle disclosed may be applied to machines for commercial use. Further I do not wish to be strictly limited to the relation specifically set forth between the hopper 19 and the shelling roller 3 or to the relative percentages between the helically arranged edges 6 and those edges 6 arranged parallel to the axis 35 of rotation of the cylinder 3 or to their respective locations. Accordingly I do not wish to be limited except by the scope of the following claims.

40 I claim:

1. A corn sheller comprising a shelling cylinder having a plurality of knobs thereon, each of said knobs presenting a shearing edge, some of said shearing edges being helically aligned with respect to each other and others of said shearing edges being aligned parallel to the axis of rotation of said cylinder, said helically arranged and parallel edges being mutually interspaced over a portion of the surface of said cylinder, means for rotating said cylinder, a yieldable, inclined sleeve extending along said cylinder, and means to feed ear corn between said sleeve and said cylinder, said sleeve resisting outward movement of the ears and said knobs being disposed helically on said cylinder whereby the corn ears are directed axially of said cylinder, said sleeve being closest to said cylinder adjacent the end thereof from which the shelled cobs are directed. 45 50 55

2. A corn sheller comprising a shelling cylinder having a plurality of knobs thereon, each of said knobs presenting a shearing edge, some of the said shearing edges being helically aligned with respect to each other and others of said shearing edges being aligned parallel to the axis of rotation of said cylinder, said helically arranged and parallel edges being mutually interspaced over a portion of the surface of said cylinder, means for rotating said cylinder, a yieldable, inclined sleeve extending along said cylinder, and a hopper extending along said shelling 60 65 70 75 cylinder for a portion of the length thereof for feeding ear corn between said sleeve and said cylinder, said knobs being disposed helically on said cylinder whereby the corn ears are directed axially of said cylinder, said sleeve maintaining 75

the ears against said cylinder under pressure and being closest to said cylinder adjacent the end thereof from which shelled cobs are directed.

3. A device of the character described comprising a sheet metal cylinder, a plurality of shearing edges disposed over the surface thereof, knobs struck up from said surface each including one of said shearing edges, said knobs being helically arranged, some of said shearing edges being aligned helically and some being aligned parallel to the axis of said cylinder, said helically aligned and parallel edges being mutually interspaced over at least a portion of the surface of the cylinder.

4. A corn sheller, comprising a shelling cylinder having a plurality of knobs thereon, each of said knobs presenting a substantially straight edge, some of said straight edges being helically aligned with respect to each other and the other of said straight edges being aligned parallel to the axis of rotation of said cylinder, said helically aligned and parallel edges being mutually inter-

spaced over at least a portion of the surface of said cylinder, means for rotating said cylinder, a yieldable sleeve extending along said cylinder, and means to feed ear corn between said sleeve and said cylinder, said sleeve resisting outward movement of the ear and said knobs being disposed helically on said cylinder, whereby corn ears are directed axially of said cylinder.

5. A device of the character described, comprising a cylinder, and a plurality of knobs projecting from the surface of said cylinder, each of said knobs presenting a substantially straight edge, the edges of some of said knobs being helically arranged with respect to each other, said last named knobs also being helically aligned on said cylinder, the edges of other of said knobs being aligned parallel to the axis of said cylinder, said helically aligned and parallel edges being mutually interspaced over at least a portion of the surface of said cylinder.
